(57) **CLAIM**

The ornamental design for an inhaler, as shown and described.

DESCRIPTION

FIG. 1 is a top, front and left side perspective view of an inhaler, showing my new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof; and,

FIG. 8 is a cross-sectional view along lines 8-8 of FIG. 6.

(Continued)

The interior elements shown in broken lines in the cross-sectional view of FIG. 8 show portions of the inhaler that form no part of the claimed design.

1 Claim, 8 Drawing Sheets
